FOUNTAIN BRUSH

Howard L. Fischer, St. Paul, Minn.

Application November 30, 1953, Serial No. 27,843

Term of patent 14 years

(Cl. D9—2)

To all whom it may concern:

Be it known that I, Howard L. Fischer, a citizen of the United States, residing at St. Paul, county of Ramsey, and State of Minnesota, have invented a new, original, and ornamental Design for a Fountain Brush, for which the following is a specification, reference being had to the accompanying drawing, forming part thereof.

Figure 1 is a side view of a fountain brush.
Figure 2 is a back view thereof.

Figure 3 is a front view thereof, looking toward the bristles in the head thereof.

Figure 4 is a bottom end view thereof.

Figure 5 is a longitudinal section on the line 5—5 of Fig. 4.

Figure 6 is a section on the line 6—6 of Figure 5. The body and brush head of my fountain brush are formed of a transparent material, the inner construction therefore being visible.

I claim:

The ornamental design for a fountain brush, as shown and described.
